UNITED STATES PATENT OFFICE.

ROYAL E. RANDALL, OF FORT MADISON, IOWA.

DESIGN FOR AN EMBLEM OR BADGE.

Application filed February 28, 1923. Serial No. 5,325. Term of patent 3½ years.

To all whom it may concern:

Be it known that I, ROYAL E. RANDALL, a citizen of the United States, residing at Fort Madison, in the county of Lee and State of Iowa, have invented a new, original, and ornamental design for an Emblem or Badge, of which the following is a specification, reference being had to the accompanying drawing, forming part thereof.

The figure is a front elevation of the new, ornamental design for an emblem or badge.

I claim:

The new and original design for an emblem or badge as shown.

ROYAL E. RANDALL.
